[57] CLAIM

The ornamental design for a combined container and closure, as shown and described.

DESCRIPTION

FIG. 1 is a perspective view of the combined container and closure according to my new design;

FIG. 2 is an elevational view showing the front of the combined container and closure of FIG. 1, the rear of the combined container and closure being the same in appearance as the front;

FIG. 3 is a top plan view of the combined container and closure of FIGS. 1 and 2;

FIG. 4 is an elevational view showing an end of the combined container and closure of FIGS. 1-3, the opposite end being the same as the end shown; and,

FIG. 5 is a bottom plan view of the container of FIGS. 1-4.
